(57) **CLAIM**

The ornamental design for the handbag, as shown and described.

DESCRIPTION

FIG. 1 is a top, front, and left perspective view of the handbag showing my new design;

FIG. 2 is a top plan view thereof;

FIG. 3 is a right side view thereof;

FIG. 4 is a left side view thereof; and,

FIG. 5 is a rear view thereof.

The characteristic feature of the handbag is its construction from a single elongated tape having zipper fasteners on each of its sides.
